DESIGN FOR A JACKET

Ruth Karplus, Jackson Heights, N. Y., assignor to Mavest Inc., New York, N. Y., a corporation of New York

Application August 15, 1938, Serial No. 79,335

Term of patent 3½ years

To all whom it may concern:

Be it known that I, Ruth Karplus, a citizen of Germany, residing at 37-12 87th Street, Jackson Heights, Borough of Queens, city of New York, in the county of New York and State of New York (assignor to Mavest Inc., New York, N. Y.), have invented a new, original, and ornamental Design for a Jacket, of which the following is a specification, reference being had to the accompanying drawing, forming part thereof.

Fig. 1 is a front view of the jacket showing my design and

Fig. 2 is a back view thereof.

I claim:

The ornamental design for a jacket, as shown.

RUTH KARPLUS.
